This diagram shows a rectangular lamp fixture with three bulb sockets. A horizontal dashed line passes through the center of the fixture. To the left of the fixture, the number '22' is written above the line and '25' is written below the line. Two lines extend from the top of the fixture towards the number '25'.

UNITED STATES PATENT OFFICE.

ADOLPH TONSAGER, OF EDMONTON, ALBERTA, CANADA.

DOOR LOCK.

Application filed July 11, 1921. Serial No. 484,006.

To all whom it may concern:

Be it known that I, ADOLPH TONSAGER, a British subject, residing at Edmonton, in the Province of Alberta and Dominion of 5 Canada, have invented certain new and useful Improvements in Door Locks, of which the following is a specification.

The present invention relates to door-locks or more particularly knob-locks. It 10 has a very simple and solid construction. It may be applied without change to right or left-hand doors, to thick or thin ones and the combination may be changed without adding or deducting any parts, only by arranging existing ones in different order. 15

In the accompanying drawings, one embodiment of the invention has been illustrated and

Figure 1 shows a vertical, longitudinal 20 section of the lock assembled in the door,

Figure 2, 3, 4, 5 and 6 are transverse sections of Fig. 1 along lines II—II, III—III, IV—IV, V—V and VI—VI respectively,

Figure 7 an axial section along line VII—VII of Fig. 1 seen from underneath,

Figure 8 a bottom plan view of the left end of the lock barrel,

Figure 9 an elevation of the lock spindle, 30 and

Figure 10 a section on line X—X of Fig. 1.

The lock consists of the following parts: The outer knob 20 and the inner knob 21 35 which are similar in appearance, are both secured on the lock-barrel 22, the inner knob 21 by means of a screw 23 in the usual manner, but in order to prevent the outer knob from being tampered with or removed without 40 authority a rivet 24 or a split pin having side projections on its shanks. Fig. 2 is used instead. The head of the pin is made smooth and preferably flush with the surface of the knob. There are provided three 45 or more holes 25 for this pin or rivet 24, see Fig. 8, in order to accommodate different thicknesses of the door; in that manner the knob 20 will be held further in or further out on the barrel 22. The inner pipe-like 50 ends of the two knobs are enclosed by the cylindrical hubs 26 of the escutcheons 27, 28 secured on either side of the door in the usual manner. The ends of the knobs 20 and 21 abut against the shoulders formed at 55 the bottom of the counter bore in the hubs,

in order to prevent axial sliding of the barrel 22 with the knobs 20, 21.

The outside knob 20 has a central, revolvable button 29 inserted in its bore and secured by small projections 30 thereon engaging in an annular groove 31 provided in said bore to prevent the button from falling out. A longitudinal slit 32 of the same cross-section as the key 53 is provided in the center of the button 32.

The barrel 22, which is mounted to revolve in the escutcheon hubs 26 extends to within a short distance of the outer faces of the hubs 20, 21 and, as has already been described, is rigidly secured to them so as 60 to revolve whenever either one of the hubs is turned. The outer end of the barrel is slotted, longitudinally in two or more places as at 33 dove-tail fashion, see Fig. 2. These 65 slots are intended to accommodate the key-plates, which are preferably made up of a number of leaves about $\frac{1}{16}$ inch thick. As

shown in Figs. 1 and 7, three active leaves 34, engaging the notches 36 in the key 53 are here provided, and a great number of blank 70 leaves 35 serve as filling pieces to properly 75 locate the active leaves 34. It will easily be understood that an almost unlimited number of combinations can be obtained by the different arrangement of the leaves, without any change in construction of the lock, thus providing for a great variety of keys. 80

In the middle portion of the barrel 22 are provided a number of longitudinal slots 85 forming spaces for the gear teeth 38 on 90 the shank 39 of the latch bolt 40. The latch bolt, which in this case also constitutes the lock-bolt, is preferably made in two parts as shown in Fig. 10, that is to say with its head 40 threaded on the shank 39. The 95 head 40 is preferably of square or rectangular transverse section, bevelled on the non-locking side in the usual manner. The middle portion 41 of the shank is cylindrical in order to accommodate a compression 100 spring 42, which acts between the head 40 and a stationary collar 43 to push the latch outwardly. The inner part 39 of the shank forms a stop-shoulder thereon abutting 105 against the collar 43 to limit the outward movement of the latch bolt. The latter is mounted in a sleeve 44 which has a square or rectangular bore to accommodate the bolt head, as has also the shield plate 45. In the sleeve 44 is provided a stop 46 to limit 110

the inward travel of the latch bolt. The collar 43 is held in place by means of one or more screw-studs 47. The lower side of the sleeve 44 has a cut 48 to accommodate the barrel 22, and its outer end is provided with a horn which locks in a corresponding recess in the shield plate 45 to prevent it from turning. The shield plate 45 is made symmetrical around the axis of the latch bolt so that it may be reversed and suitable for both right and left-hand doors.

The lock spindle 50 which is about three-quarters of the length of the barrel 22 is carried in the bore of the latter and extends from the inner end of the barrel almost to the slot 33 for the key-leaves. Its outer or left end as seen in Fig. 1 fits the bore of the barrel 22 and has a Z-shaped slot 51 engaging a stud 52 threaded in the barrel 22 forming a bayonet lock. Both end portions of the Z-slot run circumferentially on the spindle each extending fully half-way around while the middle or connecting portion thereof runs longitudinally. The extreme end of the spindle is partly cut away, leaving a lug 54 adapted to engage the side of the key 53, when the latter is inserted to turn the spindle, and a center bore 55 is provided in the latter to guide the small tit at the end of the key 53.

The middle portion of the spindle 50 is made smaller in diameter, so as to clear the teeth 38 of the latch-bolt and its inner or right hand end as seen in the figures is also of the same reduced diameter and carries on it, counting from right to left, the thimble 56, the stop ring 57, the compression spring 58 and the locking pawl 59. The latter is revolvable on the spindle and is held by the spring 58 against the shoulder 60 on the spindle. The other end of the spring abuts against the stop ring 57 which is held securely with the barrel gun by means of one or more screw studs 61. The locking pawl 59, which fits loosely in the bore of the barrel 22, projects with a lug through a longitudinal slot 62 in the barrel, and engages in a recess 63 provided in the hub 26 of the escutcheon 28, so as to be held from turning. The end portion of the inner knob 21 has a corresponding slot 64 made long enough to permit the pawl lug to enter it and become disengaged from the recess 63, when it is pushed to the right by the spindle 50.

The thimble 56, which is rigidly secured on the button, 65, is provided with one or more Z-slots 66 similar to slot 51 in the spindle 50. Studs 67 secured in the spindle 50 engage each of the slots 66 and are so positioned, that they engage the circumferential portion thereof located nearest the door in the locked position as seen in Fig. 1.

The longitudinal portions of slots 51 and 66 correspond in length to the movement of the locking pawl 59 in and out of engage-

ment with its seat, the recess 63 in the escutcheon hub 26.

The operation of the lock is as follows, the door being locked and the parts in the relative position as shown in the different figures:

The key 53 is first inserted in the knob through the slit 32 in the button 29 and made to enter between the leaves 34, Fig. 2. When the tit of the key 53 enters the central recess 55 the top edge of the key, which is level with the same side of the tit, will come in under the projecting lug 54. The key is now turned clockwise when after one-quarter turn it will have the position seen in Figs. 5 and 7, that is to say, with its flat side engaging the under side of the lug 54. After another quarter turn, or a half turn altogether, when it has turned the spindle one-quarter turn, the stud 52 stands in the longitudinal portion of the Z-slot 51. The key is now upside down to its entering portion and consequently free to slide between the leaves 34. By pushing the key inward, the spindle 50 travels with it, thereby disengaging the pawl 59 from its recess 63, so that, the outer knob 20 may now be turned clockwise. The knob being secured on the barrel 22, will cause the latter to revolve, which, being geared to the latch bolt shank 39 will retract it and the door will open. As the stud 67 was first turned and then was pushed toward the right, when the key was turned and pushed in, the stud at this time will be found in the left hand circumferential portion of the Z-slot 66, as seen in Fig. 1, so that, when the barrel 22 and the thimble 56 are revolved with the outer knob 20, the stud 67 will cause the thimble 56 and the button 65 to take the extreme right hand position, partly pushed out of the knob 21. Simultaneously, the longitudinal portion of the Z-slot 51, engaging the stud 52, as already described, will then first pass along this stud until the latter engages in the left hand circumferential portion of the Z-slot 51 and lock therewith when the barrel 22 is turned by the knob 20. It must, therefore, be evident that the spindle 50 and the pawl 59 will in this manner be held back and, as a consequence the latch bolt remain withdrawn.

Now in order to lock the door from the inside with the parts in the position just described, all that is needed is to turn clockwise the thimble 56 by means of the button 65, when the stud 67 slips into the longitudinal portion of the Z-slot 66, thereby releasing the spindle 50, which, upon continued turning until the pawl 59 registers with the recess 63, snaps back into the outward position together with the pawl 59, actuated by the spring 58. By continued turning of the button 65, the spindle 50 is revolved until it stands as shown in Fig. 1.

To lock the door when going out the button is turned counter clockwise as far as it will go, then drawn out all the way, which will bring the pawl 59 and the spindle 50 both into the right hand or unlocked positions, so that by a little more turning of the button 65 the left or outer circumferential portion of the Z-slot 51 will be engaged by the stud 52 and thus hold the pawl out of the recess 63. When lastly the outside knob 20 is turned counter clockwise upon closing the door from the outside, the parts will again take their relative positions as seen in Fig. 1 and the door will be locked.

15 What is claimed as new is:—

1. In a door lock a sliding bolt, a barrel revolvably mounted transversely to the bolt and having positive driving connection therewith, means for locking the barrel to a stationary member and other means for releasing said barrel, said other means adapted to be actuated by a door key, said other means comprising a slidable spindle in said barrel.

25 2. In a door lock a sliding bolt, a barrel revolvably mounted transversely to the bolt and having positive driving connection therewith, a slidable spindle in said barrel adapted to be turned and pushed in by a door key, a pawl slidably and revolvably mounted on said spindle and having sliding connection only with said barrel, a stationary member provided with a recess for said pawl to hold it from turning, means tending to move the pawl into said recess, said pawl adapted to be released from said recess by said spindle when pushed inward by the door key, whereby said barrel will be free to turn and retract the bolt.

40 3. In a door lock a sliding bolt, a barrel revolvably mounted transversely to the bolt and having positive driving connection therewith, a slidable spindle in said barrel, a pawl slidably and revolvably mounted on said spindle and having sliding connection with the barrel, a stationary member provided with a recess for said pawl adapted to prevent its rotation, means tending to move the pawl into said recess, a hand operated member engaging said spindle, a Z-shaped guide for the spindle permitting partial revolution at both extreme axial positions of the spindle and axial sliding in between, said pawl adapted to be released by said member through the intermediary of said spindle when the spindle is being first turned and then moved axially by said member, whereby said barrel will be free to turn and retract the bolt.

55 4. In a door lock a sliding bolt, a barrel revolvably mounted transversely to the bolt and having positive driving connection therewith, a spindle slidably and revolvably mounted in said barrel, guiding means between the spindle and the barrel permitting

partial rotation of said spindle at both of its extreme end positions and axial displacement thereof between the end positions, a pawl loosely mounted on the spindle, an abutment provided on the spindle and yielding means holding said pawl against the abutment, a longitudinal slot in said barrel engaging with the pawl and through which the pawl projects, a stationary member having a recess engaging the projecting portion of the pawl when the parts are in locked position, and means on said spindle for engaging with a door key, whereby, upon first turning and then pushing in the key, said spindle will first turn and then travel forward in the barrel, thereby releasing the pawl and permitting the turning of said barrel by hand to retract the bolt.

5. In a door lock a sliding bolt, a barrel revolvably mounted transversely to the bolt and having positive driving connection therewith, a spindle slidably and revolvably mounted in said barrel, guiding means between the spindle and the barrel permitting partial rotation of said spindle at both of its extreme end positions and axial displacement thereof between the end positions, a pawl loosely mounted on the spindle, an abutment provided on the spindle and yielding means holding said pawl against the abutment, a longitudinal slot in said barrel engaging with the pawl and through which the pawl projects, a stationary member having a recess engaging the projecting portion of the pawl when the parts are in locked position, a thimble mounted on one end of said spindle and fitting in the bore of said barrel, guiding means between said thimble and said spindle similarly constructed to said first guiding means, said two guiding means being situated at opposite ends of the spindle, said thimble upon being first turned and then moved longitudinally will cause the spindle to partake of said movements controlled by the first guiding means, thereby releasing said pawl from its recess and permitting the turning of said barrel by hand to retract the bolt.

6. In a door lock a sliding bolt, a barrel revolvably mounted transversely to the bolt and having positive driving connection therewith, a spindle slidably and revolvably mounted in said barrel, guiding means between the spindle and the barrel permitting partial rotation of said spindle at both of its extreme end positions and axial displacement thereof between the end positions, a pawl loosely mounted on the spindle, an abutment provided on the spindle and yielding means holding said pawl against the abutment, a longitudinal slot in said barrel engaging with the pawl and through which the pawl projects, a stationary member having a recess engaging the projecting portion of the pawl when the

parts are in locked position, a thimble mounted on one end of said spindle and fitting in the bore of said barrel, guiding means between said thimble and said spindle similarly constructed to said first guiding means, said two guiding means being situated at opposite ends of the spindle, said thimble upon being first turned and then moved longitudinally will cause the spindle to 10 take of said movements controlled by the first guiding means, thereby releasing said pawl from its recess and permitting the turning of said barrel by hand to retract the bolt, said pawl being retained in its released position by renewed turning of said thimble causing said spindle to rotate and be held forward by said first guiding means. 7. In a door lock a sliding bolt, a barrel revolvably mounted transversely to the bolt 20 and having positive driving connection therewith, said barrel having a longitudinal slot at its key end a plurality of thin leaves inserted in said slot adapted to engage in corresponding notches in the key, 25 a plurality of distance pieces for said leaves in said slot, whereby, upon arranging said

leaves and said distance pieces in different order, a plurality of combinations will be obtained to suit differently notched keys.

8. In a door lock a sliding bolt, a cylindrical housing therefor, said bolt comprising a protruding head, a central shank and a toothed rack, an abutment in the housing forming a guide for said shank, a spring inserted between the head and the abutment, holding the head protruding outside the door limited by the contacting of the rack against said abutment, a cylindrical barrel revolvably mounted in the door transversely to said housing, a recess in the housing accommodating said barrel, teeth on the circumference of the barrel engaging said bolt rack, and means in said barrel for locking it from turning, said means being adapted to be released by a door key. 45

In testimony whereof I affix my signature in presence of two witnesses.

ADOLPH TONSAGER.
